UNITED STATES PATENT OFFICE.

JERYMIAH B. REDMOND AND LYNNLY C. ADAMS, OF VICKSBURG,
MISSISSIPPI.

SEPARABLE FRICTION-HANGER.

SPECIFICATION forming part of Letters Patent No. 653,921, dated July 17, 1900.

Application filed September 25, 1899. Serial No. 731,646. (No model.)

To all whom it may concern:

Be it known that we, JERYMIAH B. REDMOND and LYNNLY C. ADAMS, citizens of the United States, residing at Vicksburg, in the 5 county of Warren and State of Mississippi, have invented a new and useful Improvement in Separable Friction-Hangers, of which the following is a specification.

Our invention relates to an improvement in 10 friction-hinges in which the friction between the leaves of the hinge and the pintle is depended upon to retain the movable portion to which the hinge is secured in any desired position, and has for its object to provide 15 what might be termed a "separable friction-hanger," whereby the movable member may be detached from its support without unscrewing or detaching any of the parts.

With this object in view the invention consists in providing that portion of the pintle 20 which projects from the socket with angular sides and a hanger-plate with a seat for the angular portion of the pintle and a pivoted securing member adapted to abut against the 25 hanger-plate and retain the pintle in place.

Our invention further consists of certain 30 details of construction, which will be herein-after fully described, recited in the claim, and illustrated in the drawings, in which—

35 Figure 1 is a perspective view of a mirror, showing our invention applied. Fig. 2 is a cross-section of a support to which our hanger is secured. Fig. 3 is a front elevation of the hanger, the pintle-retaining member being 40 swung at right angles to its normal position; and Fig. 4 is a detail perspective view of a special form of pintle used in connection with our invention.

45 Referring now to the several parts by reference-numerals, 5 designates a mirror to which are secured two hinge-leaves 6, having sockets 7 and a friction-plate 8, designed to bear upon the cylindrical portion 9 of the pintle 10, which is held in the socket 7 by the plate, the tension of which is regulated by the screws 11.

The pintle 10 is provided with an extension 12, preferably rectangular in cross-section and which is designed to rest in a seat in the separable hanger. This hanger comprises a plate

14, of suitable width and thickness, having openings, as at 15 and 16, whereby it can be secured to the support, and terminating at its lower end in a curvature or hook 16^a, forming a seat in which the angular end of the 55 pintle rests. It will be noticed that the side of the pintle next the plate fits snugly against the same, and to hold and retain the pintle in this position we have provided the pivoted latch or locking member 17, pivotally 60 secured to the plate 14 and held snugly therein by means of a screw 16^b. On the lower end of this locking member is a right-angular lip or extension 18, which projects over the angular portion of the pintle, and 65 as the downwardly-projecting portion 19 thereof abuts against the outer side of the pintle the same is prevented from turning. In operation these hinges will be used on transoms, mirrors, or, in fact, any device in 70 which a stationary support and pivoted support are employed, and by simply swinging the locking member 17 to the position shown in Fig. 3 the movable member can be lifted out of the seat for the purpose of being cleaned, 75 stored, moved, or for any other reason.

It will thus be seen that we have provided a very simple effective means whereby the desired result can be attained, and while the exact configuration of the several parts has 80 been described we do not limit ourselves thereto, but reserve the right to make such slight changes and alterations as would properly come within the scope of our invention without departing from the spirit thereof. 85

Having thus fully described our invention, what we claim as new, and desire to secure by Letters Patent of the United States, is—

In a friction-hinge the combination with the pintle thereof, the sides of which are parallel 90 a short distance, of a hanger having a seat in which the end of the pintle is adapted to rest and a pivoted locking member adapted to engage one of the sides of the pintle to prevent its turning, substantially as described. 95
